(57) **CLAIM**

The ornamental design for a cryosurgical probe as shown and described.

DESCRIPTION

FIG. 1 is a perspective view of an embodiment of a cryosurgical probe showing our new design having a first curved rod and a first environmental handle;

FIG. 2 is a front view thereof (the back view is a mirror image of the front view);

FIG. 3 is a top view thereof;

FIG. 4 is a bottom view thereof;

FIG. 5 is a left view thereof;

FIG. 6 is a right view thereof;

FIG. 7 is a right view thereof without the first environmental handle;

FIG. 8 is a perspective view thereof having a second environmental handle;

FIG. 9 is a front view thereof having the second environmental handle (the back view is a mirror image of the front view);

FIG. 10 is a perspective view of another embodiment of a cryosurgical probe showing our new design having a second curved rod and the first environmental handle;

FIG. 11 is a front view thereof (the back view is a mirror image of the front view);

FIG. 12 is a top view thereof;

FIG. 13 is a bottom view thereof;

FIG. 14 is a left view thereof;

FIG. 15 is a right view thereof;

FIG. 16 is a right view thereof without the first environmental handle;

FIG. 17 is a perspective view thereof having a second environmental handle; and,

FIG. 18 is a front view thereof having the second environmental handle (the back view is a mirror image of the front view).

The broken lines throughout the drawing figures depict an environmental handle that forms no part of the claimed design.
